RAIL ANCHOR

Filed April 9, 1929

UNITED STATES PATENT OFFICE

LOUIS R. PARSONS, OF STRONGHURST, ILLINOIS

RAIL ANCHOR

Application filed April 9, 1929. Serial No. 353,822.

This invention relates to an improvement in rail anchors, in the use of which the rail is anchored with respect to the tie against longitudinal creeping.

The invention comprehends a unitary or integral structure which may be readily connected to or disconnected from the rail, and which when in place will have such relation to the rail and tie that any creeping tendency in the rail will act to compel an increased wedging cooperation between the rail anchor and the rail, to thereby additionally resist any creeping tendency in the rail.

The primary object of the present invention is the provision of a rail anchor which, as a result of its construction, is, when applied, disposed in wedging cooperation with the rail supplemented by a clamping action designed to inherently increase the wedging cooperation, to thereby insure the absolute fixing of the anchor and rail in the direction of rail creeping.

A further object of the present invention is the provision of a wedging column which extends from the clamping jaw portion of the anchor to underlie and engage the tread of the rail, with such wedging column at all times at an inclination to the vertical plane of the clamp portion of the anchor, so that when the anchor is driven to place, the wedging column has a wedging relation with the ball or tread of the rail, incident to and as a direct result of applying the anchor.

The invention is illustrated in the accompanying drawings, in which:

Figure 1 is a view showing the rail in transverse section and the anchor in front elevation.

Figure 2 is a side view of the same.

Figure 3 is a perspective view of the anchor.

Figure 4 is a side elevation of the upper portion of the wedging column on an enlarged scale.

Figure 5 is an end elevation of the anchor showing particularly the normal inclined or offset relation of the wedging column.

The improved rail anchor, which is preferably constructed of round high tempered steel of appropriate diameter, comprises a

tie engaging bar 1 adapted to underlie the rail, and centrally formed with a rounded depending offset 2. The bar 1 is terminally formed at one end with a hook 3, designed to engage with and beyond one edge 4 of the base flange 5 of an ordinary rail 6, the rail of course including the web 7 and ball or tread portion 8.

The rail engaging bar 1, at the end opposite the hook 3, is formed in a return bend to provide what may be termed a clamp having upper and lower jaws 9 and 10. These jaws are normally spaced apart to permit the passage of the edge of the base flange 5 between them, the clamping space between the jaws being restricted at the inner end, as at 11, to insure a clamping engagement with the upper and lower surfaces of the base flange. This clamping space is, outwardly of the restricted portion 11, gradually enlarged, as indicated at 12.

The upper jaw 9 of the clamp of the anchor is extended upwardly as a wedging column 13. This wedging column is of a length exceeding the distance between the upper jaw 9 of the clamp and the bottom of the ball or tread portion 8 of the rail. The column inclines inwardly from the end of the clamp jaw 9 toward the web of the rail, and also inclines from the end of the clamp jaw 9 at an angle to the vertical plane passing through the clamp and bar 1.

Thus, the rail anchor includes the bar 1 and clamp which are disposed in the same vertical plane, and the wedging column which rises from the clamp at a distinct angle to this vertical plane. It is understood that the anchor is a substantially rigid structure, and that it is normally constructed with the wedging column at the angle described. Thus, in applying the rail anchor, the wedging column is normally in wedging cooperation with the ball or tread of the rail.

In the application of the anchor, the clamp is engaged with one edge of the base flange of the rail, with the bar 1 underlying the base flange of the rail and the hook 3 immediately adjacent that edge of the base flange remote from the clamp. In this position the wedging column rises from the clamp at an angle

to the vertical and underlies the outer portion of the ball or tread of the rail. The anchor is then driven into place, until finally the hook 3 engages the edge of the base flange of the rail. During this movement, the wedging column has been driven into wedging co-operation with the ball of the rail, and incident to the fact that the wedging column is inclined from the vertical, the wedging action of the upper end of the column with the ball of the rail tends to slightly turn the clamp from its vertical plane, as indicated clearly in Figure 2. There is of course, under this slight distortion of the clamp, an inherent tendency in the jaws of the clamp to return to the normal position, that is to a position in which the clamp proper is in a vertical plane. This inherent tendency obviously tends to move the free end of the wedging column in a more effective wedging cooperation with the tread of the rail. As the wedging action of the column cannot be increased by this tendency of the clamp, it is apparent that the inherent tendency of the clamp tends to effectively maintain the wedging cooperation of the column, while the wedging cooperation of the column tends to maintain the slight distortion of the clamp. The wedging action and clamping action are thus more effectively maintained as a direct result of the application of the anchor, and without other operations than the mere application of the anchor. The upper or free end of the wedging column, while slightly rounded and properly finished for smooth cooperation with the surface of the tread of the rail, is inclined with respect to a vertical plane passing through the column, such inclination being indicated at 14 in Figure 4, and being in the direction of wedging movement of the column. This insures effective surface bearing between the end of the column and the ball of the rail, and further prevents any possibility of the wedging column ever assuming a vertical position. The characteristic and important feature of the present rail anchor is the provision of a wedging column which is normally at an inclination to the vertical plane passing through the rail bar and clamp of the anchor. This inclination of the wedging column insures a wedging cooperation between said column and the ball of the rail as a direct result of the ordinary and usual application of the anchor. That is to say, with the anchor applied in the usual manner, the wedging cooperation of the column and the slight distortion of the clamping action, result as a direct incident to the application of the anchor, and without requiring any further driving actions, applications of force, or operations on the anchor. The mere driving of the anchor to place secures the full result. Of course it is understood that the anchor is applied adjacent the side of a tie, as indicated at 15, with the wedging action of the

column arranged to resist creeping of the rail.

It is to be particularly emphasized that a salient and underlying feature of importance of the present anchor is that its wedging column is inclined to the vertical plane of the anchor in the normal relation of the anchor parts. That is to say, the extreme upper end of the wedging column is materially offset from the plane of the remaining anchor parts, so that the wedging column is in wedging position as a direct result of and during the application of the anchor.

What is claimed to be new is:

1. A rail anchor adapted for clamping co-operation with the base flange of a rail and having a portion to bear against the supporting tie, said rail anchor including a wedging column normally at an inclination to the plane of the anchor.

2. A rail anchor including a tie engaging bar, a rail engaging clamp at one end thereof, and a wedging column extending upwardly from the clamp and inclined to a plane of the clamp.

3. A rail anchor having a tie engaging bar, a rail flange engaging hook at one end thereof, a rail flange engaging clamp at the opposite end thereof, and a wedging column rising from the clamp and normally at an inclination to the plane of the anchor.

4. A rail anchor having a bar to underlie the rail, a clamp to engage one edge of the base flange of the rail, and a wedging column normally inclined to the plane of the anchor and designed for wedging cooperation with the ball of the rail in the application of the anchor, the wedging cooperation of the column and rail ball correspondingly distorting the clamp to cause the inherent clamping pressure to increase the wedging engagement of the column with the ball of the rail.

5. A rail anchor having means whereby the anchor may be secured to the rail, and a wedging column having its free terminal offset from the plane of the anchor, whereby to provide an inclined wedging column having a normal wedging position.

6. A rail anchor including means for connecting the anchor to the rail, and including a wedging column inclined with respect to the plane of the anchor proper and also inclined with respect to a vertical plane transverse the anchor proper, whereby in normal position the wedging column is normally inclined in two directions.

7. A rail anchor including means for connecting the anchor to the rail and a wedging column forming part of one of said means and normally inclined with respect to the plane of the anchor, said wedging column in the application of the anchor increasing the holding effect of the rail engaging means of the anchor.

8. A rail anchor having means to remov-

ably engage the base flange of a rail and including a wedging column rising from the anchor proper at an inclination to the plane of the anchor, said wedging column providing a rigid non-yielding member normally in wedging relation to the rail in and during the application of the anchor.

5 9. A rail anchor constructed of metal substantially circular in cross section and of uniform diameter throughout, said anchor including a clamp to engage one edge of the base flange of a rail, a bar to underlie the base flange of the rail, a hook to engage the opposite edge of the base flange of the rail, 10 and a wedging column rising from one arm of the clamp at an angle to the plane of the anchor.

15 10. A rail anchor constructed of metal substantially circular in cross section and of uniform diameter throughout, said anchor including a clamp to engage one edge of the base flange of a rail, a bar to underlie the base flange of the rail, a hook to engage the opposite edge of the base flange of the rail, 20 and a wedging column rising from one arm of the clamp at an angle to the plane of the anchor, said wedging column being also inclined with respect to a transverse vertical plane passing through the anchor.

25 20 In testimony whereof I affix my signature.
LOUIS R. PARSONS.
